ATTORNEYS.

UNITED STATES PATENT OFFICE.

HARRY H. McCLELLAN, OF DAYTON, OHIO.

FOOT-SUPPORTER.

1,374,669.

Specification of Letters Patent.

Patented Apr. 12, 1921.

Application filed February 7, 1920. Serial No. 356,872.

To all whom it may concern:

Be it known that I, HARRY H. McCLELLAN, a citizen of the United States, residing at Dayton, in the county of Montgomery and State of Ohio, have invented certain new and useful Improvements in Foot-Supporters, of which the following is a specification, reference being had therein to the accompanying drawing.

10 This invention relates to foot supporters and has for its object to provide improved flexible braces or bands adapted to fit closely about the ankle and instep of the foot and to be adjusted to compensate for variations or changes effected in the foot by the pressure exerted thereon.

15 The main object of the invention is to provide devices of this character made of thin material and adapted to be worn inside the shoe, also inside the hosiery, if desired, which may be worn without discomfort to the wearer and which may be adjusted by suitable lacings to exert pressure on the bound portions of the foot whereby changes 20 in the structure of the foot may be gradually effected.

25 The improved device is especially adapted for treatment of deformed feet, commonly known as "flat foot" or "fallen arch," and has been found effective in connection with prescribed foot exercise and muscular treatment in gradually restoring fallen arches to their normal position.

30 An important feature of the invention consists in the adjustability of the bands to conform to the gradual change in the foot structure. Thus the required pressure may be brought to bear continuously on the affected parts to restore the same to normal.

35 In this respect the adjustable bands have a marked advantage over the well known practice of wearing metal pads or supports inside the shoe to support the arch, in which no provision is made to compensate for the yielding of the fallen arch structure, except by substituting pads of variable shapes or sizes.

In the accompanying drawing;

40 Figure 1 is a detail view showing the adjustable bands applied to a foot;

45 Fig. 2 is a perspective view of the device detached showing the manner of arranging the adjustable bindings; and

50 Fig. 3 shows a modified form of the device applied to a foot.

55 It will be understood that the adjustable

bands may be made of any suitable material and that the size and shape may be varied to suit variable foot deformities, the essential features of the invention consisting of a 60 suitable cover jacket or pads at the intersection of the bands which may be worn with comfort next the skin or outside the hose which protects the foot from direct contact with the adjusting bands by means of which 65 pressure is brought to bear upon the portions of the foot which are to be treated.

In the form shown in Fig. 1 the inner part of the supporter consists of the jacket or glove 1 which is made of two opposite 70 pieces of leather 2 sewed together at the bottom and back to form the jacket which is adapted to be laced over the ankle, as shown at 3, a flap strap 4 being secured to one of the pieces 2 and projecting under 75 the opposite piece 2, under the lacing to prevent discomfort to the foot when the lacing is drawn taut. The lower portion of the jacket is adapted to extend around the foot over the instep, having opposite extensions 5 and 6, which are brought close together and may overlap at their forward edges when the jacket is in position on the foot, an open space 7 being formed between the parts 5 and 6 and the lacing 3 to permit free action of the ankle when the jacket is worn. A clearance aperture 8 is also provided in the jacket for the heel of the foot to permit free movement of the heel, also to provide for a closer fit of the jacket to 90 the foot.

No novelty is claimed as to the details of the jacket described, the arrangement being similar to well known forms of foot braces or lacing jackets, the form here shown being used only for the purposes of illustrating the invention which consists in using in combination with the jacket or otherwise the adjustable bands by means of which restoring of fallen arches is effected.

100 The adjusting bands may be made of any suitable material and arranged in any suitable manner as required for the purposes of the invention. As here shown, the bands consist of two non-elastic tapes 9 and 10 105 which are secured, respectively, at one end to the extensions 5 and 6 of the lower portion of the jacket, the ends 5 and 6 being padded or made double thickness as shown, to prevent discomfort to the foot when the 110 tapes are drawn taut.

As here shown the tape 9 is fastened in

the part 5 on one side of the foot and is passed outwardly under the part 6 to the opposite side of the foot, thence through a keeper 11, downwardly across the sole of the foot, upwardly on the opposite side of the foot, through a keeper 12, passing above the heel to the opposite side of the foot again, and terminating in a buckle strap 13.

The tape 10 is arranged similar to the tape 9 but in the opposite direction, the tape being fastened in the part 6, passing under the part 5 and through a keeper 14 in the jacket, thence downwardly crossing the tape 9 on the bottom of the foot, thence upwardly through a keeper 15, again crossing the tape 9 above the heel and terminating in a buckle 13^a, whereby the ends of the tapes 9 and 10 may be joined together and drawn taut.

From the foregoing detailed description it will be understood that the tapes 9 and 10 may be drawn taut to any desired extent, the practice being in the application of the invention in treating fallen arches to exert as much pressure at the points A, B, C and D as may be borne with comfort. At the point A the adjusting tapes are fastened, as above stated, in the jacket extensions 5 and 6, making what is in effect an unyielding support for one end of the tapes and thus providing for the pressure that is applied at B and C when the tapes are drawn taut. At B the crossed tapes pass directly over the tendon of Achilles and the fibula or small bone of the lower leg, which together with the tibia or large bone of the leg are more or less abnormal in their relation to the foot at their lower ends in fallen arches on account of the lengthened fallen arch.

At C the tapes cross on the bottom of the foot and the combined pressure of the two tapes is exerted upwardly on the muscles of the foot and on the inner end of the os calcis or the prominent bone of the heel, also on the tarsal bones which form the arch or instep of the foot.

From D the tension of the tapes is also exerted upwardly on the foot at C, the pressure at D permitting the rear ends of the tarsal bones and the front end of the os calcis bone which articulates therewith to rise to re-form the arch, the tibia and fibula bones of the leg also being pressed into normal position by the pressure exerted at B. It will be observed that the pressure at C is exerted upwardly on the arch of the foot from four directions, the combined actions of the tapes exerting relatively a very high pressure at this point; the pressure at B is also exerted from four directions, all tending to draw the lower ends of the bones of the leg inwardly to normal relation with the ankle and instep.

It is well understood in physiology that

bone and muscle organizations will respond readily to the application of external treatment of this character, the requirement being to continue the treatment regularly, preferably in connection with foot exercise which is prescribed, the time required for the foot structure to be restored to normal position and normal strength, when the treatment may be discontinued.

The modified form of the device shown in Fig. 3 is essentially the same in principle as shown in Figs. 1 and 2, the modification consisting in eliminating the lacing jacket 1 and substituting foot-easing pads 16, 17, 18 and 19 at the points on the foot where the pressure is applied. The pressure bands 20 and 21 are applied and function substantially the same as in the form shown in Figs. 1 and 2.

It will be understood, of course, that further modifications may be made in the device relative to the details of construction and arrangement without departing from the underlying principle of the invention as defined in the appended claims.

Having thus fully described my invention, what I claim as new and desire to secure by Letters Patent, is:—

1. In a foot support, the combination with a jacket adapted to fit closely a portion of the foot, of a plurality of bands coöperating with said jacket, secured relative to each other above the instep and wound about the foot in opposite directions, said bands intersecting at places and adjustable at their ends relative to each other, whereby variable pressure may be exerted on the foot from different directions at said points of intersection.

2. In a foot support, the combination, with a jacket adapted to fit closely a portion of the foot, of a plurality of bands coöperating with said jacket, wound about the foot in opposite directions, intersecting above the heel and on the bottom of the foot and adjustable to exert pressure on the foot at said points of intersection.

3. In a foot support, the combination, with a jacket adapted to fit closely a portion of the foot, of a plurality of adjustable bands interlaced and coöperating with said jacket, wound about the foot in opposite directions, intersecting on the bottom of the foot, whereby pressure may be exerted on the foot at the point of said intersection.

4. In a foot support, the combination, with a jacket adapted to fit closely a portion of the foot, of a plurality of adjustable bands interlaced and coöperating with said jacket, wound about the foot in opposite directions, intersecting on the bottom of the foot, whereby pressure will be exerted on the foot at said point of intersection from four directions.

5. In a foot support, the combination, of

a plurality of adjustable bands wound about the foot in opposite directions, intersecting above the heel and on the bottom of the foot, whereby pressure may be exerted on the 5 foot from different directions at said points of intersection.

6. In a foot support, the combination, with bands secured relative to each other above the instep and wound about the foot 10 in opposite directions, intersecting at points and adjustable at their ends relative to each other, whereby variable pressure may be exerted on the foot from different directions at said points of intersection.
- 15 7. In a foot support, the combination, with a plurality of adjustable bands wound about the foot in opposite directions, intersecting above the heel and on the bottom of

the foot, whereby pressure may be exerted on the foot from different directions at said 20 points of intersection, and means applied beneath said bands to ease the foot at the points of intersection of said bands.

8. In a foot support, the combination, with a plurality of adjustable bands wound 25 about the foot in opposite directions, intersecting above the heel and on the bottom of the foot, whereby pressure may be exerted on the foot from different directions at said points of intersection, and means applied beneath said bands to ease the foot at the 30 points of concentrated pressure of said bands.

In testimony whereof, I affix my signature.

HARRY H. McCLELLAN.
